UNITED STATES PATENT OFFICE.

CLETUS N. ALLERDING, OF MANSFIELD, OHIO

STEERING-WHEEL.

1,321,876.

Specification of Letters Patent.

Patented Nov. 18, 1919.

Application filed December 7, 1917. Serial No. 205,963.

To all whom it may concern:

Be it known that I, CLETUS N. ALLERDING, a citizen of the United States of America, residing at Mansfield, in the county of Rich-
5 land and State of Ohio, have invented cer-
tain new and useful Improvements in Steer-
ing-Wheels, of which the following is a
specification.

This invention relates to an improvement
10 in steering wheels for automobiles or the like,
wherein a solid non-metallic rim is employed
and adapted to be connected to the terminals
of the arms of the spider.

The present invention is directed to the
15 method of forming the respective members
for the particular connection, and also to the
article resulting from such method.

In steering wheels, the generally accepted
20 type combines the solid wooden rim and
the metallic spider, and it is desirable and
important that the connection be such as to
avoid breakage or marring of the rim under
the strain of use, that such connection re-
25 main practically rigid under all conditions,
and that such connection be formed with a
view to avoid marring the appearance of
the rim and spider, in order that the steer-
ing wheel present the ornamental and pleas-
30 ing effect demanded by the user.

In thus combining a wooden or similar
35 rim, with a metallic spider to secure the ad-
vantages noted, the first essential is the abso-
lute rigidity of the connection in a forma-
tion which will distribute the strain of use
throughout an extended area of the wooden
40 rim to avoid splitting or breaking the lat-
ter.

The present method consists therefore in
forming in a wooden rim a series of recesses
45 at a particular point and at a particular
angle with relation to the horizontal diam-
eter of the rim to not only conceal the
connection from above but insure the distri-
bution of the strain on the rim in use in a man-
ner to present the maximum resistance
thereto.

The method more specifically consists in
forming at predetermined points in the in-
ner surface of the rim a series of apertures
50 opening through the rim surface and of
countersink formation. These apertures are
formed on a line of cut at approximately
15° to the horizontal diameter of the rim
55 with the upper marginal edge of such aper-
tures on a line, or approximately so, with
such horizontal diameter of the rim. Fur-

thermore, these apertures are formed with
the usual circular tool, which, due to the
double curvature formation of the rim, re-
sults in apertures of oval formation having
60 their major axis in the circumferential plane
of the rim, and the countersink walls at the
extremities of the major axis of maximum
depth, gradually decreasing to the minimum
depth on the minor axis. The terminals of
65 the spider arms are formed with head ends
to accurately fit the apertures or recesses, a
wood screw further uniting the parts.

As a result of this formation the twisting
or lateral strain on the rim is at an angle
70 to the horizontal and resisted by a very con-
siderable area of the material of the rim,
while the end strain is resisted by recessed
walls of maximum depth, inclined so that
said strain is converted into a wedging ac-
75 tions, to resist separation.

A steering wheel constructed in accord-
ance with the present method, is shown in
the accompanying drawings, in which:

Figure 1 is a broken plan showing a por-
80 tion of a steering wheel constructed in ac-
cordance with the present method.

Fig. 2 is a similar view of a bottom plan.

Fig. 3 is a broken perspective of a portion
85 of the rim, illustrating particularly the for-
mation of the recess.

Fig. 4 is a transverse section, inverted,
showing the connection between the spider
and rim.

Fig. 5 is a broken longitudinal section
90 showing the connection.

Fig. 6 is a face or end view of the spider
arm terminal.

Fig. 7 is a side view of the same.

The invention is here shown as a steer-
ing wheel for automobiles combining a solid
non-metallic, preferably wooden rim 1 se-
cured to a spider 2, the latter having the
usual arms 3 which are to be terminally con-
nected to the rim.

The improved method is directed to this
connection, and as illustrated consists in
forming, at predetermined points in the rim
1 a series of recesses 4. These recesses, as
will be more particularly apparent from
105 Fig. 4, are formed in the under side of the
inner surface of the rim, being cut at an
angle 45° to the horizontal diameter of the
rim, with the upper margin of such recess
in line with such horizontal diameter. The
110 recess is cut with a round countersink tool,
and by reason of the circumferential and

transverse curvature of the material of the rim, the recess resulting from such round tool is of oval configuration, with its major axis circumferentially of the rim and its minor axis transverse thereof. Furthermore, this cut forms inclined walls 5 at the limits of the major axis of much greater depth than the inclined walls 6 at the limits of the minor axis, as clearly shown in Figs. 10 3, 4 and 5.

Each recess therefore is of oval configuration, of greater length than width, with maximum length walls at the ends thereof, and with the entire recess at an angle of approximately 45° to the horizontal, and practically wholly concealed in a true plan view of the rim.

The terminals of the arms of the spider are formed with what may be termed heads 20 7 shaped to accurately conform and fit into the said recesses, the outer surfaces 8 of such heads presenting plain surfaces at an angle approximating 45° to the axis of the spider, and bearing squarely against similar 25 surfaces forming the base or bottoms of the recesses. The inner surfaces of the heads as 9 are shaped to conform to, and present, in so far as possible, a continuation of the outer surface of the rim. An ordinary wood 30 screw 10 unites the heads and rim, being countersunk in the metallic heads, and taking into the material of the rim.

As thus formed the connection is practically concealed from the upper surface of 35 the rim, but particularly and of more importance presents a rigid, strain-resisting joint. For example, as the rim and spider ends fit together on an angle of 45° to the horizontal, and from beneath the horizontal, 40 it is apparent that a downward strain on the rim is resisted by practically the full area surface of the head 7 throughout the vertical dimension of the rim, and the lateral or twisting strain on the rim is resisted by the comparatively extended bearing 45 surfaces or inclined walls 5 of the recess. As these walls are inclined it is apparent that this twisting strain is converted into a wedging action, thereby resisting any tendency to separate the connections, or to split 50 or mar the rim at the joint.

The steering wheel constructed by the present method presents, therefore, all the advantages required in the commercial 55 steering wheel. The gripping surface is absolutely unmarred or unbroken, with the connection proper on practically the under side of the rim so that there is presented practically no obstruction to the free sliding 60 movement of the hand in operating the wheel; the connection between the spider and rim is rigid; the connection is so formed that advantage is taken of the maximum possible resistance of the material of the 65 rim to the strain and stress incident to the

use of the wheel; and the oval or elongated formation of the head permits the side edges of the arms of the spider to merge into the surface of the head on lines forming a merging curvature with the meeting surface of the rim, to add to the pleasing lines at the juncture of the spider and rim. 70

Having thus described the invention, what is claimed as new is:—

1. A rim for steering wheels, comprising 75 a circular structure of substantially oval shape in cross section, with spider-receiving recess arranged at an angle to the horizontal plane of the rim, and of oval edge formation in the plane of the rim and with a substantially circular base, the wall of the recess being of maximum height longitudinally of the rim and of minimum height transversely of the rim.

2. A rim for steering wheels comprising 80 a circular structure of rounded shape in cross section, and formed with spider terminal receiving recesses at determinate points, each of said recesses being formed on the inner surface of the rim below and at an 85 angle to the horizontal plane of the rim, each recess having an oval outer edge in the plane of the surface of the rim and a substantially circular base, the wall of the recess being of greatest height in the longitudinal peripheral line of the rim and gradually reduced from such part of greatest height to a part of least height in the transverse line of the rim. 90

3. A steering wheel comprising a rim having 95 recesses formed below the horizontal diameter thereof with the bottoms at an angle to such horizontal diameter, and spider arms having terminal heads formed at an angle to the rim, the heads also being formed 100 to fit and fill the recesses in such a manner as to provide a smooth and unobstructed surface of the rim at the points of the attachment of the arm terminal heads to the rim. 105

4. A steering wheel comprising a rim having 110 oval shaped recesses formed in its inner surface, with inclined side walls and bottoms at an angle to the horizontal diameter thereof, and a spider having arms the free ends of which are formed at an angle to correspond to the angle of the said recesses and of such a contour as to fill and merge with the external surface of the rim thereby providing a continuous, smooth and unobstructed rim surface at the points of connection of 115 the free ends of the spider arms to the rim. 120

5. A steering wheel comprising a rim having 125 oval shaped recesses formed in the inner surface thereof with inclined walls and a spider having arms the free ends of which are formed to fit and fill the recesses of the rim in such a manner as to conform and coincide with the external surface of the rim thereby presenting a smooth and continuous surface, and screws for uniting the parts. 130

6. A steering wheel comprising a rim having angularly related recesses formed below the horizontal diameter thereof and a spider having arms the free ends of which are 5 formed and adapted to accurately fit and fill said recesses thereby presenting a continuous surface line, with respect to the rim thereby presenting a smooth and unobstructed rim surface, and fastening means to unite the 10 arms to the rim, observable from one side only when the parts are connected.

7. An article of manufacture comprising a rim having a series of recesses formed at an angle in the inner edge thereof and a 15 spider provided with arms the free ends of which are angularly related to the body portion and which are provided with heads

which engage and fill said recesses thereby presenting a rim of uniform, unbroken and unobstructed exterior surface lines. 20

8. A steering wheel comprising a rim of oval cross section having a series of angularly related recesses formed therein by means of a round tool the side walls thereof also being inclined and a spider provided 25 with arms the terminals of which are angularly related thereto and formed of such shape and size to fit and fill said recesses so as to restore the rim surface to smooth and unbroken surface lines at the points of connection of the spider arms to the rim. 30

In testimony whereof I affix my signature.

CLETUS N. ALLERDING.
